LOUIE F. METCALF, OF GREENVILLE, ALABAMA, ASSIGNOR TO FLORENCE D. METCALF,
OF GREENVILLE, ALABAMA.

UNION WORKING GARMENT.

1,411,120.

Specification of Letters Patent. Patented Mar. 28, 1922.

Application filed June 14, 1921. Serial No. 477,609.

To all whom it may concern:

Be it known that I, LOUIE F. METCALF, a citizen of the United States, residing at Greenville, in the county of Butler and State 5 of Alabama, have invented certain new and useful Improvements in Union Working Garments, of which the following is a specification.

The present invention relates to union 10 working garments and has for its object to produce a union working garment which will be easy to manufacture, neat in appearance and which will be capable of withstanding hard use for a long period.

15 With these and other objects in view, as will appear below, the invention consists of a union working garment embracing certain features which are old and in addition thereto certain features which are new.

20 The annexed drawings show particular exemplifications of garments made in accordance with the present invention. In said drawing, Fig. 1 represents a front view of the principal portions of the device, Fig.

25 2 represents a view of the same with the coat portion opened in order to fully display the location and arrangement of a reinforcing strip embraced within the present invention.

30 Fig. 3 represents a section on the line 3—3 of Fig. 1 showing the construction of the reinforcement strip and the pocket and the relation of these two parts to the fabric forming the jacket portion. Fig. 4 repre-

35 sents a back view of one modification of the garment, a portion of the same being broken away to show the inner flap which extends downwardly from the belt or waist band.

Fig. 5 represents a back view of another modification of the back and Fig. 6 represents a side view showing the lower part of the side of the coat or jacket portion, the belt and the upper part of the trousers portion and the drop-seat in a raised position.

40 Referring now to said drawings, the union garment consists essentially of a jacket portion having a left front 10 and a right front 11, a trousers portion 12, the two being joined along the line 13, and at the point of junction, a belt 14 is provided. The rear 45 part of the trousers portion can be let down for convenience in putting on and taking off the garment. This drop-seat is attached to suspenders 17, passing over the shoulders and attaching to buttons 18, or 50 other suitable fastening devices. Wire but-

ton holes 19 can be provided for this purpose. The button 18 preferably is attached through the coat portion of the garment and also through the vertical reinforcing strip 15. A suitable rivet for fastening the button may be employed as shown at 20 in Fig. 2.

The reinforcement strip 15 is preferably stitched to the jacket portion, with the bottom of the belt, also from the bottom of the belt up to the top of said strip 15, and across the top thereof, and across the top of the belt, said strip lying between the belt and the fabric of the jacket portion. It is pref-

erably stitched with two or more lines of 70 stitching at these points. This strip extends upwardly on the inside of the jacket portion to a short distance above the point of attachment of the button 18. This strip is also stitched to the jacket portion, preferably

75 with two or more lines of stitching across the top, and preferably with two or more lines of stitching along each of its vertical edges. Thus it will be seen to be rigidly attached to the jacket portion, around the entire edge of the strip, and also along the top of the belt. When the reinforcement strip is on the inside of the garment, the lower edge thereof will preferably be (as

80 shown) between the belt and the fabric of 85 the garment which accordingly adds to the strength and simplifies the manufacture of the garment.

The reinforcement strip, the belt, the jacket, and the trousers are all preferably 90 made of the same material. This strip greatly strengthens the front of the garment as a whole, and furnishes additional support for the buttons which co-act with the sus-

95 penders attached to the drop-seat whereby the entire garment is materially strengthened and made more capable of withstanding hard wear.

The garment may be provided with any 100 suitable pockets. In Fig. 1 are shown some patch pockets on the coat portion, the pocket 30 opening at its top 31, the pocket 32 preferably opening at its side 33. The front trousers pockets are provided with openings such as those shown at 34 and 35, respectively. 36 represents an opening of another small pocket suitable for holding matches or the like, which may be provided if desired. Obviously the reinforcement strip 15 could be (and in certain classes of work preferably 110

is) placed on the outside of the jacket rather than on the inside thereof.

I claim:

1. A union overall garment comprising a jacket portion and a trousers portion, a drop-seat on the trousers portion, suspenders carried on the said drop-seat, the front of the jacket portion being provided with reinforcement strips extending from the junction of the jacket portion and trousers portion, upwardly to the breast, such strips being stitched all around the edges thereof to said garment, fastening means on the jacket portion at the upper parts of said strips, the said fastening means being attached through said jacket portion and said strips, and being adapted for attachment to said suspenders.
2. A union overall garment comprising a

jacket portion and a trousers portion and 20 having a belt at the point of union of said portions, a drop-seat on the trousers portion, suspenders carried on the said drop-seat, the front of the jacket portion being 25 provided with reinforcement strips extending from the belt upwardly to the breast, said strips being located on the inside of said jacket portion, and being stitched thereto on all the edges of said strips, and to said belt at some portions of said strips, fastening means on the jacket portion at the upper parts of said strips, the said fastening means being attached through said jacket portion and said strips, and being adapted 30 for attachment to said suspenders. 35

In testimony whereof I affix my signature.

LOUIE F. METCALF.
